UNITED STATES PATENT OFFICE.

AUGUST LEMKE, OF DETROIT, MICHIGAN.

GARDEN-SPRINKLER.

1,368,269.

Specification of Letters Patent. Patented Feb. 15, 1921.

Application filed November 24, 1919. Serial No. 340,402.

To all whom it may concern:

Be it known that I, AUGUST LEMKE, a citizen of the United States of America, residing at Detroit, in the county of Wayne and State of Michigan, have invented certain new and useful Improvements in Garden-Sprinklers, of which the following is a specification, reference being had therein to the accompanying drawings.

10 The invention relates to sprinklers more particularly designed for use in the sprinkling of gardens, and it is the object of the invention to obtain a construction which may be easily adjusted and without the necessity of getting into the wet or mud. To this end the invention consists in the peculiar construction, arrangement and combination of parts as hereinafter set forth.

15 In the drawings:
20 Figure 1 is a side elevation of the sprinkler;

Fig. 2 is a plan view thereof;
Fig. 3 is a vertical section.

In the sprinkling of gardens it is desirable to have a construction of sprinkler that rises above the growing plants and which is capable of being introduced between rows. It is also desirable to distribute the water with uniformity and if the range is necessarily limited, this requires adjustment from time to time. With my improved construction the sprinkler is in the form of a laterally-extending perforated arm, which is mounted upon a vertical standpipe of sufficient height to clear the tops of the plants, said standpipe being connected at its base with a laterally-extending supply pipe and being also supported on a wheeled base to facilitate its movement in and out from between rows. To uniformly distribute the water the sprinkler arms are rotatively adjustable about the standpipe and provision is made for effecting this adjustment from a point beyond the range of the sprinkler, so as to avoid the necessity of getting into the wet or mud.

50 In detail, A is a vertical standpipe rising from a base fitting B, which is supported on ground wheels C engaging an axle D. E is a sprinkler arm at the upper end of the standpipe A and which preferably extends radially on opposite sides of said standpipe. F are extension arms of the sprinkler E, which are connected thereto by fittings G which permit of folding when not in use and

thereby limiting the dimensions of the device. Brace wires I from the extremities of the arm E pass over a strut H to stiffen the sprinkler arm. J is a supply pipe extending laterally from the base fitting B, 60 being detachably jointed by the coupling K at a radial distance from the standpipe, substantially the same as the fittings G, said supply conduit having an extension L beyond the coupling of sufficient length to 65 pass beyond the range of the sprinklers. This supply conduit has a swivel engagement with the fitting B and at its opposite end has a swivel engagement with a fitting M upon the hose or other extension conduit 70 leading to the tap. The sprinkler arm E is fixedly attached to the inner conduit N, which passes downward within the standpipe A and has a swivel engagement therewith. O and O' are intermeshing bevel 75 gears, or other means, for rotatively connecting the adjacent ends of the conduit J and the conduit N. This connection permits of turning the arm E through the medium of the conduits J and L and as the outer 80 end of the latter conduit is beyond the range of the sprinkler, this adjustment may be effected without getting into the wet.

The fitting B is provided with stuffing boxes P and P' for forming a water tight 85 swivel joint respectively between the conduits J and N and said fitting. There is also provision for introducing the bevel gears O and O' through orifices normally closed by caps Q and Q' and through one of 90 these orifices there may be introduced a deflector member R, which forms an easy bend for the passage of the water, and avoids impeding its velocity. To provide access to the stuffing box P', the standpipe A is coupled to the fitting B through the medium of spaced arms S bolted, or otherwise secured, to ears T and T'. This permits access to the cap P² of the stuffing box P', so that the latter may be tightened as often as necessary to maintain a water tight joint. U is a ball thrust bearing between the upper end of the standpipe A and the sprinkler arm E, which supports the weight and reduces friction.

100 When the sprinkler is not in use, the extension arms F are folded, as indicated in dotted lines in Fig. 1, and the conduit L is detached from the conduit J. This makes a comparatively compact structure which may 105 110

be easily stored. In use, the conduit J is first coupled to the conduit L, the extension arms F are turned to extend outward, and the conduit L is connected with its supply 5 hose or other connection. The operator may then use the conduit L as a handle and introduce the standpipe and sprinkler between rows of plants, rolling it to the desired position upon the wheels C. The water is then turned on and will be discharged 10 through jet openings in the arms E and F, sprinkling the plants within its range. From time to time the angle of the arms E and F may be altered by rotating the conduit L through a suitable handle, such as 15 L', and which through the medium of the bevel gear wheels O and O' will rotate the vertical conduit N. The latter being fixedly connected to the arm E, will turn said 20 arm upon the ball bearing U. After the area within the range of the swinging arms E and F has been completely sprinkled, the standpipe may be adjusted in position also through the medium of the conduit L and 25 whenever necessary, the device may be removed from between the rows and re-inserted between two other rows.

What I claim as my invention is:

1. A sprinkler comprising a stand pipe 30 provided at its upper end with an angularly adjustable lateral sprinkler arm, means in which the stand pipe is rotatably supported, and a laterally-extending supply pipe journaled in the supporting means of 35 the stand pipe and operatively connected to the stand pipe to turn the latter.
2. A sprinkler comprising a base, a stand pipe journaled therein and provided at its upper end with sprinkler arms, a supply 40 pipe journaled near one end in the base transversely to the stand pipe, and means in the base coupling the supply and stand pipes to turn together on their respective axes.
3. A sprinkler comprising a supporting 45 base, a stand pipe journaled in the base and provided with lateral sprinkler arms above the base, a supply pipe swiveled in the base, the latter forming a coupling between the stand pipe and supply pipe, means within 50 the base operatively connecting the stand and supply pipes for turning the stand pipe by rotation of the supply pipe, and means forming a swivel engagement for de-

tachably securing the supply pipe to a conduit.

55

4. A sprinkler, comprising a vertical standpipe, a wheeled base for supporting the same, a supply pipe extending laterally from said base and having a swivel engagement therewith, a conduit having a swivel engagement with the other end of said supply pipe, a sprinkler arm rotatively mounted at the upper end of said standpipe, and a driving connection between said supply pipe and sprinkler arm for rotatively adjusting the latter by the rotation of the former.

60

5. A sprinkler, comprising a standpipe including a base fitting, a laterally-extending supply pipe having a swiveled engagement with said base fitting, a conduit within said standpipe having a swiveled engagement with said base fitting, a sprinkler arm connected to the upper end of said last-mentioned conduit, intermeshing bevel gears on the adjacent ends of said supply pipe and conduit connected to the sprinkler arm, and a swiveled engagement between said supply conduit and a supply conduit therefor permitting the rotation of the former to effect a rotative adjustment of said 70 sprinkler arm.

75

6. A sprinkler, comprising a standpipe, a supply pipe having a swivel connection with the base of said standpipe, a sprinkler arm 85 mounted at the upper end of said standpipe, connections between said supply pipe and sprinkler arm for rotatively adjusting the latter by rotation of the former, and an extension arm for said sprinkler arm having a swivel engagement therewith permitting of 90 folding.

95

7. A sprinkler, comprising a standpipe, a fitting at the base thereof provided with a capped orifice, a supply pipe having a swiveled engagement with said fitting, a sprinkler arm mounted at the upper end of said standpipe, a conduit within said standpipe connected to said sprinkler arm, and intermeshing gears engaged respectively with 100 said supply conduit and conduit within the standpipe, said gears being insertible within said fitting through the aperture therein when uncapped.

105

In testimony whereof I affix my signature.

AUGUST LEMKE.
